GEORGE S. RADFORD, OF NEW CANAAN, CONNECTICUT, ASSIGNOR TO BELLING HEMINWAY COMPANY, OF NEW YORK, N. Y., A CORPORATION OF CONNECTICUT

SPOOL FOR THREAD

Application filed May 25, 1929. Serial No. 365,851.

My invention relates to spools for thread and contemplates improved means for holding the free end of the thread against unintentional unwinding.

5 In accordance with my invention I mount a resilient member upon the spool and I provide another member between which and said resilient member the thread may be inserted, and pursuant to this underlying conception 10 I contemplate certain further features contributing effectively to the desired end.

My invention is illustrated in the accompanying drawings in which:

Figure 1 is an end view of a spool embodying my invention;

Figure 2 is an axial sectional view thereof, taken on the plane of the line 2—2 of Figure 1 and looking in the direction indicated by the arrows;

20 Figure 3 is an elevational view thereof; and

Figure 4 is a perspective view of a special form of tack which is a feature of my invention.

25 The spool itself is of wood or other material and, except for features presently to be pointed out, is of conventional form comprising a cylindrical barrel 5, having an axial bore 6, and the flange 7 at each end. The 30 thread wound upon the spool is indicated at 8.

The end of the spool is mortised, preferably open at its periphery, as indicated at 9, this mortise being shallow, of the depth of

35 the straight portion of the flange 7, and circular in form. This particular form, however, is not controlling; the mortise may be of any form and it may be closed as distinguished from opening at the periphery of the 40 spool.

An insert, in the form of a disc 10, is lodged in the mortise 9 and, preferably, it fits and fills the mortise exactly so as to preserve the conventional contour of the spool.

45 The insert 10 is of readily compressible or resilient material, such as rubber or cork, and it is held in the mortise 9 by being compressed in the process of insertion therein, 50 that is it is held therein by its own tendency

to expand, or it may be held therein by simple friction, or by cement or other means.

As a specific feature of my invention I provide such other means in the form of a tack which may alone, or additionally, hold the 55 insert 10 in place and which serves the purpose of providing the other member between which and the resilient insert the loose end of the thread may be caught. Thus I provide the tack 11, the shank of which passes through the insert 10 and into the body of the spool, as illustrated in Figure 2, and the head of which presses down upon the top of the insert. The free end of the thread, shown at t, 60 may therefore be inserted under the head of the tack 11, as illustrated, the resiliency of the insert 10 permitting this.

65 The arrangement thus described is such that the thread holding means lies substantially within the conventional contour of the spool. If desired, of course, the head of the tack may be pressed down to a position entirely within the mortise 9, and the insert 10 may be slightly reduced in thickness, if desired, in order to make this possible.

70 As illustrated in Figure 4, the shank of the tack 11 is provided under the head with a cutting edge 12 against which the thread may be drawn to cut it. The lower edge 13 of the head of the tack is also sharp so that it, too, may be used as a cutting edge against which the thread may be drawn to cut it if desired.

I claim:

1. A spool for thread comprising a body, 85 a resilient pad, and a tack holding said pad to said body, whereby the free end of the thread may be inserted between the head of said tack and said pad, the shank of said tack having a cutting edge thereon.

90 2. A spool for thread comprising a body, a resilient pad, and a tack holding said pad to said body, whereby the free end of the thread may be inserted between the head of said tack and said pad, the edge of said head 95 being a cutting edge.

3. A spool for thread mortised at one end adjacent the periphery thereof, a resilient member disposed in said mortise, and another member at the upper face of the resilient 100

member and between which and said resilient member the free end of thread wound on said spool may be inserted.

4. A spool for thread comprising a body of wood having a mortise in the end thereof, an insert of resilient material disposed in said mortise, and a tack passing through said insert into said body with its head engaging said insert, whereby the free end of said thread may be inserted between said head and said body and held in place by the resiliency of said insert.

5. A spool for thread comprising a cylindrical body with a flange, an insert of resilient material lodged in the end of said body and exposed at the periphery of the respective flange, and a tack passing through said insert into said body with its head engaging said insert, whereby the free end of said thread may be inserted between said head and said body and held in place by the resiliency of said insert.

In witness whereof, I hereunto subscribe my name this 16th day of May, 1929.

GEORGE S. RADFORD.
